(57) **CLAIM**

The ornamental design for a heart-shaped convex blind spot mirror for safer driving, as shown and described.

DESCRIPTION

FIG. 1 is a front, bottom perspective view of an heart-shaped convex blind spot mirror for safer driving, showing my new design;

FIG. 2 is an exploded front, bottom perspective view thereof;

FIG. 3 is an exploded rear, top perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The dash-dot broken lines represent stitching that forms no part of the claimed design.

The bracketed lines in FIG. 2 represent a separation in the structure to illustrate the exploded configuration and depict the spatial relationship between the components, serving solely for explanatory purposes and not forming part of the claimed design.

The bracketed lines in FIG. 3 represent a separation in the structure to illustrate the exploded configuration and depict the spatial relationship between the components, serving solely for explanatory purposes and not forming part of the claimed design.
